Primary Examiner — Austin Murphy(74) *Attorney, Agent, or Firm* — Oblon, McClelland, Maier & Neustadt, L.L.P.(57) **CLAIM**

The ornamental design for an intercom system, as shown and described.

DESCRIPTION

FIG. 1 is a top view of an intercom system according to an embodiment of the invention;

FIG. 2 is a front elevational view thereof;

FIG. 3 is a right side elevational view thereof;

FIG. 4 is a left side elevational view thereof;

FIG. 5 is a rear elevational view thereof; and,

FIG. 6 is a bottom view thereof.

Any dashed lines in the drawings depict environment and/or disclaimed subject matter and form no part of the claimed design. Further, Applicant reserves the right to disclaim or claim any portion or portions of the design(s).
